UNITED STATES PATENT OFFICE.

WILLIAM J. HALSALL, OF GREENFIELD, INDIANA.

ROLLING-MILL.

1,110,625.

Specification of Letters Patent. Patented Sept. 15, 1914.

Application filed November 8, 1913. Serial No. 799,836.

To all whom it may concern:

Be it known that I, WILLIAM J. HALSALL, a citizen of the United States, residing at Greenfield, county of Hancock, and State of Indiana, have invented certain new and useful Improvements in Rolling-Mills, of which the following is a specification.

My invention relates to rolling mills and the object of my invention is to provide an improved rolling mill for reducing old railroad iron to bars of uniform cross section and subsequently shaping them into bars of cruciform cross section to be used as fence posts.

15 A further object of my invention is to provide a device as mentioned of such construction that old railroad iron may be reduced to bars of merchantable iron.

20 A further object of my invention is to provide means for adjusting rollers relative to each other to secure the maximum efficiency in the action of the rollers upon the material.

25 A further object of my invention is to provide in a rolling mill means for adjusting the rollers relative to each other and means for adjusting a portion of one of the rollers with relation to the coöperating roller.

30 Other objects will appear hereinafter.

With these objects in view my invention consists generally in a pair of coacting rollers provided with suitable bearings and having their peripheries shaped to reduce the 35 railroad iron or old rails to bars by successive passes between the same.

My invention further consists in a pair of rollers as mentioned arranged to reduce rails of various sizes to a uniform height 40 preparatory to severing the same into separate bars, means for scoring the web by a second pass, and means for severing the ball and the flange portions or the ball portion only, by a third pass.

45 My invention further and more particularly consists in a rolling mill having the coöperating rollers as above stated with the trunnions of the rollers mounted in bearings arranged in suitable housings and 50 means on one of the housings for shifting one of the bearings to adjust the respective roller longitudinally with relation to the coöperating roller.

55 My invention further consists in a pair of superimposed coöperating rollers of the

character above stated in which the trunnions are mounted in bearings arranged in suitable housings, means for shifting the bearings of the lower roller to adjust said roller longitudinally with relation to the upper roller and means for adjusting the bearings for the journals of the upper roller to adjust the upper roller vertically with relation to the lower roller.

My invention further consists in a pair of 65 rollers shaped with coöperating ribs and grooves for the purpose mentioned, means for shifting the rollers longitudinally with relation to each other to adjust certain of said grooves and ribs and means whereby 70 certain portions of one of said rollers may be adjusted independently of the remaining portions.

My invention further consists in a rolling mill comprising a pair of coöperating rollers and guides adjacent said rollers to prevent curling of the material, said guides comprising plates having apertures therein corresponding in shape to the spaces between the rollers.

80 My invention further consists in various details of construction and arrangements of parts all as will be more fully described hereinafter and particularly pointed out in the claims.

85 My invention will be more readily understood by reference to the accompanying drawings forming a part of this specification and in which—

Figure 1 is a front elevation of a rolling 90 mill embodying my invention in its preferred form, one of the housings and a portion of one of the rollers being illustrated in section, Fig. 2 is a side elevation of the same, Fig. 3 is a detail section on the line 95 $x-x$ of Fig. 2, Fig. 4 is a similar section on the line $y-y$ of Fig. 2, Figs. 5 and 6 are detailed views illustrating in elevation the guide plates for the material, Fig. 7 is a detail view illustrating the construction of 100 one end of one of the rollers, equipped with a shearing collar to be used for severing the flange from the web, Fig. 8 is a view similar to Fig. 4 illustrating a modified form of the adjusting device, and Fig. 9 is an elevation of a pair of rollers employed for shaping the bars formed from the rail into bars of cruciform cross section for use as fence posts.

105 Referring now to the drawings, 1 and 2 110

indicate a pair of superimposed rollers provided with the trunnions 3-3 and 4-4 respectively mounted in bearing blocks 5 and 6. 7 indicates the housings for the bearing blocks 5 and 6 which are preferably U-shaped in cross section as indicated in Figs. 3 and 4. The trunnions or journals 3 and 4 are provided with ribs 8 fitting within corresponding grooves 9 in the bearing blocks whereby the rollers are in fixed relation longitudinally to said blocks, that is, there is no free play longitudinally between the trunnions and the bearings. The rollers 1 and 2 have their peripheries shaped as at 10 to compress the rails to a uniform height by passing the same therethrough after heating; as at 11 to score the web of the rail below the ball when it is desired to sever the ball only from the rail, and as at 11' 20 to score the web adjacent both the ball and the flange when the rail is to be sheared into three pieces. To shear the ball from the web a shearing edge 12 is formed on the roller 1 to coöperate with a shearing edge 12' on the roller 2.

To insure a proper coaction of the shearing edges 12 and 13 to secure the maximum efficiency of the device, is one of the primary objects of my invention and to this 30 end I provide means for adjusting the lower roller having the shearing edge 12' longitudinally with relation to the upper roller having the shearing edge 12, and provide additional means for adjusting the edges 35 13 and 13' with relation to each other.

To adjust the edges 12 and 12' I provide means for adjusting one of the bearing blocks 6 accordingly. A pair of set screws 40 14-14 are threaded through the outer wall of the housing and bear against the outer face of one of the bearing blocks 6. See Fig. 4. A third screw 15 passes loosely through a bore 16 in the outer wall of the housing and is threaded into the block 6. 45 A collar 17 is formed on the screw 15 abutting the outer face of the housing and it is obvious that by means of the screws 14 and 15 the position of the block 16 may be readily adjusted in the housing to shift the lower roller 2 longitudinally with relation to the upper roller 1, thereby adjusting the relation of the edges 12-12'. After the block 6 is properly adjusted it is held firmly 50 in position by a set screw 6' threaded through the housing and bearing against the same.

Adjacent the edge 12 of the roller 1, said roller is reduced in diameter and threaded as at 18 and upon this portion 18 is threaded 60 an auxiliary section 19. I provide two of the sections 19, one form as illustrated in Fig. 1 and the other as shown in Fig. 7. When it is desired to shear the ball only from the web I use the form shown in Fig. 65 1; but should I desire to shear both the ball

and flange from the web I employ the form shown in Fig. 7. As shown in Fig. 7 the section 19 is provided with a shearing edge 13 and the necessary grooves for accommodation of the adjacent portion of the flange 70 and web as is well understood. A squared portion 20 is provided to facilitate turning the section 19 on the threaded portion 18, and it is obvious that by turning said section the relation of the edge 13 to the 75 edge 13' on the roller 2 may be readily adjusted. Washers 21 of various thicknesses may be interposed between the member 19 and the shouldered end of the roller 1 if preferred.

To adjust the distance between the rollers 1 and 2 when in operation so as to regulate the thickness of the product, I provide means for vertically adjusting the bearing blocks 5. This consists of a screw 22 threaded through the upper wall of the housing and swiveled as at 23 into the bearing block 5 to permit vertical adjustment and at the said time prevent longitudinal movement of the roller. One side of the block 5 is provided with a V-shaped groove 24 into which fits a correspondingly shaped vertically disposed member 25 held in position by a pair of set screws 26 threaded through the adjacent wall of the housing and having their 90 ends embedded in said member.

To prevent the metal from curling as it passes between the rollers I provide guide plates 27 and 28 upon opposite sides of the rollers and held in position in any suitable manner, not shown. These plates are provided with apertures 29 of a shape to conform to the material passing through the rollers and are arranged a proper distance from the rollers to prevent the objectionable 105 curling naturally resulting from the passes between the same.

In Fig. 9 I have shown a pair of rollers 30 and 31 provided with coöperating shaped ribs and grooves 32 and 33 for shaping the 110 bars passing from the rollers 1 and 2 into bars of cruciform cross section. By having the groove 33 of considerable depth and the ribs 32, a high class finished article is produced without rough or feather edges. 115

In Fig. 8 I have illustrated a modified form of adjusting device adapted to be used with housings of the ordinary form, that is, those not provided with the outer wall through which the screws 14 and 15 are 120 threaded. In said figure 7' indicates the housing. Secured to the housing adjacent the bearing block 6 is a U-shaped member 7" comprising a pair of arms 7' embracing the sides of the housing and intermediate 125 portion 7". The screws 14 are threaded through the portion 7' of the member 7" and the screw 15 is swiveled in the same and threaded into the block as in the foregoing form. Screws 7' threaded through the arms 130

7^a hold the yoke or member 7" securely in position.

From the above description the operation of the device will be clear and need not be 5 recited in detail.

1 claim:—

1. In a rolling mill, a pair of coöperating rollers having shearing edges and provided with trunnions, bearing blocks for said trunnions, housings for said blocks, means for preventing longitudinal movement of one of said rollers, a screw extending through an aperture in said housing and threaded into one of the bearing blocks of the other 15 roller and a pair of screws threaded through said housings adjacent the first said screw and bearing against the end of said block.

2. In a rolling mill, a roller provided with a pair of peripheral shearing edges, a second roller provided with a shearing edge co-operating with one of the shearing edges on the first-mentioned roller, said second mentioned roller having a threaded extension, an auxiliary section threaded upon said extension and provided with a shearing edge co-operating with the second shearing edge of the first mentioned roller and means for 25

adjusting the first mentioned shearing roller, substantially as described.

3. In a rolling mill, a pair of coöperating 30 rollers provided with coöperating shearing edges, trunnions on said rollers, housings at the ends of said rollers, bearing blocks in said housings for said trunnions, coöperating means on said trunnions and said blocks 35 to prevent independent longitudinal movement of said trunnions relatively to said blocks, the bearing blocks of one of said rollers being provided with grooves extending at right angles to the direction of the 40 roller, keys adjustably secured to said housings and engaging in said grooves, means for raising said blocks in the direction of the grooves, and means for adjusting the other of said rollers longitudinally with relation 45 to the first said roller, substantially as described.

In testimony whereof I have signed my name to this specification in the presence of two subscribing witnesses.

WILLIAM J. HALSALL.
